UNITED STATES PATENT OFFICE

HERBERT F. PATTON, OF CLEVELAND, OHIO.

ARC-LAMP FOR STEREOPTICONS, &c.

No. 904,640.

Specification of Letters Patent.

Patented Nov. 24, 1908.

Application filed May 13, 1907. Serial No. 373,214.

To all whom it may concern:

Be it known that I, HERBERT F. PATTON, citizen of the United States, resident of Cleveland, county of Cuyahoga, and State of Ohio, have invented a new and useful Improvement in Arc-Lamps for Stereopticons or the Like, of which the following is a specification, the principle of the invention being herein explained and the best mode in 10 which I have contemplated applying that principle, so as to distinguish it from other inventions.

This my present invention relates to improvements in arc lamps, and particularly in 15 arc lamps designed for use in stereopticons, magic lanterns, or similar optical instruments, whereon it is necessary or desirable to have the light employed in the instrument proceed from a fixed point with respect to a 20 system of lenses or the like. As needs no explanation, there has been considerable difficulty encountered in the employment of arc lamps in the connection stated, for the reason that the carbons are gradually consumed 25 and hence require to have their positions shifted from time to time pending the operation of the instrument. Now it is only with great care that such positions can be altered without throwing the luminous point to one 30 side or the other of the optical axis of the condenser, referring for instance to the case of the magic lantern or stereopticon. It is with a view to overcoming these several difficulties that my invention has been devised, 35 said invention consisting of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings: Figure 1 is a 45 plan view of an arc lamp, with the carbons removed therefrom, embodying in one approved form the several improvements constituting my invention; Fig. 2 is a side elevation of the same with the carbons shown in 50 position thereon; Fig. 3 is a diagrammatic plan representation of the relative arrangement of my lamp and the lenses of the magic lantern where a direct current is employed for operating the lamp; Fig. 4 is a similar 55 representation of the arrangement maintaining where alternating instead of direct cur-

rent is employed; Fig. 5 is a transverse cross section taken on the line 5—5, Figs. 1 and 2; Fig. 6 is a side elevation of a stereopticon showing my improved arc lamp operatively 60 positioned with respect thereto; and Fig. 7 is a longitudinal cross section of one arm of the lamp and parts appurtenant thereto.

As will be seen from an inspection of the drawings just described the mechanism constituting my improved lamp is suitably mounted in a tubular base A that is designed to be secured in the base of the box of the lantern or stereopticon, in which the lamp is housed, Fig. 6. Such variation as may be required to adapt base A for use in different types of lanterns is of course comprehended, the detailed construction of the base forming no part of the present invention and that here shown being merely typical. The base 65 of the lamp proper comprises a circular plate B bearing on its under side a pin or stud b that is adapted to fit in tubular base A. By means of a set screw a mounted in the latter the plate B may be secured in any desired 70 angular position about the pivotal axis thus provided. Horizontally projecting from base plate B of the lamp and at right angles to each other are two arms B' B². The terminal portions b³ b⁴ of these arms are bent 75 upwardly and form bearings for the outer ends of threaded feeding rods b' b², the inner ends of which are mounted in similar bearings provided in an upwardly turned flange b⁵ integral with plate B. The one feed shaft 80 b' is hollow, as is the usual construction, and within the same is disposed a second shaft b⁶ that bears on its inner end, above plate B, a bevel gear b⁷ meshing with a similar gear b⁸ on the inner end of shaft b². By means of 85 milled feeding wheels b⁹, b¹⁰ mounted on the respective outer ends of tubular and inner shafts b' b⁶, such shafts may be rotated either 90 separately or both together. Shafts b' and b² are exteriorly screw threaded and engage 95 with correspondingly threaded nuts c constituting the base members of the carbon holders C. Such base members of the holders C rest slidably on the arms B', B² horizontally projecting from plate B, Fig. 5. 100 Upon the upper face of each of these members are provided carbon clamps consisting of two transversely slidable clamp members c' that are opened and closed with respect 105 to each other by means of an adjusting screw c² rotatably mounted on the top of the base members and having oppositely threaded 110

portions respectively engaging the two clamp members, as will be readily understood.

Having thus described the mechanism of my improved arc lamp the mode of its operation when in use may be easily explained. The carbons D secured in the carbon holders will obviously lie parallel with the respective horizontally extending arms B' B² of the device. Furthermore, in view of the 10 clamping means employed, these carbons are at the same time preserved in strict central position with respect to such arms. This result follows whatever the diameter of the carbon, and is of importance in view of the 15 further result attained by this feature of construction along with the disposition of the pivotal axis of the device, whereby the intersection of the central lines of the carbons is located in such axis. Upon a proper 20 adjustment hence, of the holders C along such arms it will be evident that the points of the carbons will be brought into juxtaposition directly over the plate B. Such plate in turn, it will be recalled, is located 25 directly over the pivotal axis about which the device as a whole is capable of swinging. This axis being once accurately located with respect to the optical axis of the condenser lens, in connection with which it is desired 30 to employ the lamp, it will be evident that no further adjustment in this particular will be necessary, either laterally or vertically. Once the proper focus has been determined, the only possible adjustment, in other words, 35 that is required while the lamp is in operation, is to bring the two points of the carbons sufficiently close together to cause the formation of the arc when the current is turned on. This adjustment is performed 40 with facility by the means provided. Where the direct current is employed the positive carbon is obviously advantageously disposed parallel with the axis of the lens system of the instrument, since the crater formed in 45 the end of such carbon constitutes the superior source of light. This is the arrangement illustrated in Fig. 3. Where, however, the alternating current is employed, the consumption, or burning away, of the carbons being equal, it is well recognized that 50 it is desirable to have the two carbons disposed at an equal angle with respect to such axis. This disposition, in the case at hand, is easily accomplished by simply swinging 55 the lamp about its pivotal axis until the respective carbons with their supporting arms lie at an angle of forty-five degrees to such axis, Fig. 4.

So far as maintaining the luminous point 60 of light, or the arc, specifically speaking, properly centered, is concerned, it will be clear no more difficulty is to be apprehended when the carbons are thus arranged than when the first described disposition is the 65 one utilized. This is in marked contrast to

the troubles incident to a similar use of prevailing types of lamps, although in many no provision for such use is made at all. It is finally to be noted that any of the various sizes of electric arc lamp carbons in current 70 commercial use may be employed in my improved lamp. The limitations as to length and diameter imposed in present lamp constructions being done away with, this for the reason that as seen the carbons are centered whatever their diameter, and both carbons projecting laterally in a horizontal plane the unconsumed portion can be easily accommodated, which is not the case in most types of lantern mounted as they are on 80 solid bases where the carbon rods are both vertical, or the one vertical and the other horizontal.

Other modes of applying the principle of my invention may be employed instead of 85 the one explained, change being made as regards the mechanism herein disclosed, provided the means stated by any one of the following claims or the equivalent of such 90 stated means be employed.

I therefore particularly point out and distinctly claim as my invention:—

1. In a stereopticon or the like, the combination with the lens system, of an arc lamp comprising means respectively adapted to 95 support two carbons in intersecting lines lying in a plane including the axis of such system, said means being independently adjustable along such lines and being jointly oscillatory about an axis passing through 100 the point of intersection of such lines at right angles to such plane.

2. In a stereopticon or the like, the combination with the lens system, of an arc lamp comprising a horizontal support pivotally mounted about a vertical axis intersecting the axis of such system, said support being formed with two arms extending radially with respect to such vertical axis, and carbon holders adjustable along said arms 110 respectively and adapted to support carbons parallel therewith.

3. In a stereopticon or the like, the combination with the lens system, of an arc lamp comprising a horizontal plate pivotally mounted about a vertical axis intersecting the axis of such system, said plate being vertically adjustable and being provided with two horizontal arms extending radially with respect to such pivotal axis and carbon 120 holders adjustable along such arms respectively and adapted to support carbons parallel therewith.

4. In a stereopticon or the like, the combination with a suitable base, of a lens system and an arc lamp supported thereon, said arc lamp comprising a horizontal plate pivotally mounted about a vertical axis in said base intersecting the axis of such system, said plate being vertically adjustable 125

and provided with two relatively rectangularly disposed horizontal arms extending radially with respect to such pivotal axis, a shaft rotatably mounted parallel with each 5 of said arms, a carbon holder movably mounted along each of said arms and having threaded engagement with the corresponding shaft, said holders being adapted to support carbons centrally over and in alignment with the corresponding arms, and means for rotating said shafts independently of each other.

5. In a stereopticon or the like, the combination with a lens system, of an arc lamp 15 comprising a horizontal support pivotally mounted about a vertical axis intersecting the axis of such system, said support being formed with two arms extending radially with respect to such vertical axis, and a 20 carbon holder movably mounted along each of said arms, each of said holders including two clamp members mounted so as to be movable transversely of the corresponding arm and an adjusting screw provided 25 with oppositely threaded portions engaging said clamp members respectively.

6. In a stereopticon or the like, the com-

bination with a suitable base, of a lens system and an arc lamp mounted thereon, said lamp comprising a horizontal plate pivotally 30 mounted about a vertical axis in said base and intersecting the axis of such system, said plate being provided with two relatively rectangularly disposed horizontal arms extending radially with respect to said pivotal 35 axis, a shaft rotatably mounted parallel with each of said arms, a carbon holder movably mounted along each of said arms, each of said holders including a base member having threaded engagement with said 40 corresponding shaft, two clamp members mounted so as to be transversely movable on said base member, and an adjusting screw rotatably held in said base member and provided with oppositely threaded portions 45 engaging said clamp members respectively and means for rotating said shafts independently of each other.

Signed by me, this 10th day of May, 1907.

HERBERT F. PATTON.
